(57) **CLAIM**

The ornamental design for a neck therapy pad, as shown and described.

DESCRIPTION

FIG. 1 illustrates a front perspective view of a neck therapy pad;

FIG. 2 illustrates a front view of the neck therapy pad thereof;

FIG. 3 illustrates a back view of the neck therapy pad thereof;

FIG. 4 illustrates a left side view of the neck therapy pad thereof;

FIG. 5 illustrates a right side view of the neck therapy pad thereof;

FIG. 6 illustrates a top view of the neck therapy pad thereof;

FIG. 7 illustrates a bottom view of the neck therapy pad thereof; and,

FIG. 8 illustrates a bottom perspective view of the neck therapy pad thereof.

The broken lines shown in the drawings are for purpose of illustrating portions of the neck therapy pad which form no part of the claimed design.

1 Claim, 7 Drawing Sheets
